Des. 189,100
Patented Oct. 25, 1960

189,100

CHRISTMAS TREE STAND

Robert Berning, Garfield, Ohio (12324 Oak Park Blvd.,
Cleveland, Ohio), and Anthony Jasion, Garfield, Ohio
(13505 Broadway, Cleveland, Ohio)

Filed May 4, 1959, Ser. No. 55,760

Term of patent 7 years

(Cl. D35—3)

Fig. 1

Fig. 2

Fig. 4

Fig. 5

Fig. 5

Fig. 1 is a top plan view of a Christmas tree stand showing our new design;

Fig. 2 is a front elevational view thereof;

Fig. 3 is a bottom plan view thereof;

Fig. 4 is a vertical cross-sectional view of one of the feet thereof taken along line 4-4 of Fig. 1; and

Fig. 5 is a vertical cross-sectional view of one of the feet thereof taken along line 5-5 of Fig. 1.

We claim:

The ornamental design for a Christmas tree stand, as shown.
